UNITED STATES PATENT OFFICE

2,362,331

TWIN-PAILS HOLDER

Anna Weber, Pittsburgh, Pa.

Application October 30, 1942, Serial No. 465,272

1 Claim. (Cl. 224—45)

This invention relates to a holder, and while primarily designed and intended for carrying a pair of conventional type of scrubbing pails used for cleaning purposes, it will be obvious that the holder may be employed for holding receptacles for any other purposes wherein it is found to be applicable.

Important objects and advantages of the invention are to provide a holder of the character described, which is particularly adapted for carrying a pair of conventional type of scrubbing pails, which allows the removal of either of the latter therefrom for independent emptying purposes, which embodies novel and conveniently operable means for securing the pair of pails therein or for releasing the latter therefrom, which is simple in its construction and arrangement, durable, compact, attractive in appearance, and comparatively economical in its manufacture and use.

With the foregoing and other objects in view which will appear as the description proceeds, the invention resides in the novel construction, combination and arrangement of parts herein specifically described and illustrated in the accompanying drawing, but it is to be understood that changes in the form, proportions and details of construction may be resorted to that come within the scope of the claim hereunto appended.

In the drawing wherein like numerals of reference designate corresponding parts throughout the several views:

Figure 1 is a side elevational view of a holder constructed in accordance with the invention, and carrying a pair of ordinary scrubbing pails.

Figure 2 is a sectional view of the holder on line 2—2, Figure 1.

Figure 3 is an enlarged end elevational view of the holder, partly in cross section and with portions thereof being broken away.

Referring in detail to the drawing 1 and 2 respectively denote a pair of similar scrubbing pails. Each of the latter is of the conventional metal type and well known construction, and includes the usual tapering side wall 3 and bail 4.

The improved holder comprises a continuous strip or strap metal loop, which is shaped to form a pair of similar carrier bands, respectively indicated at 5 and 6, and a constricted neck between the latter. The carrier bands are horizontally aligned, and are spaced from each other by the interposed constricted neck, which latter consists of a pair of spaced, parallel disposed neck mem-

bers, respectively indicated at 7 and 8, and forming portions of the loop structure.

A transversely extending cross-bar 9 is disposed between the neck members 7 and 8. The cross-bar is formed with depending end portions 10 which are permanently secured to respective neck members by means of rivets 11, welding, or in any other suitable manner.

A carrying handle 12 is fixed in position between the upper ends of a pair of connecting arms 13. The latter are disposed vertically upward and have their lower ends permanently secured to respective neck members 7 and 8 by means of the rivets 11, or in any other suitable manner. The carrying handle extends parallel to the cross-bar 9 and at right angles with respect to the longitudinal disposition of the aligned carrier bands 5 and 6.

The connecting arms 13 gradually taper in width throughout their lengths, having reduced upper ends while the lower ends thereof are of widths preferably commensurate to the lengths of respective neck members 7 and 8 to which latter they are attached. Such attachment of the connecting arms in conjunction with the attachment of the cross-bar 9, as stated, provides a rigid holder structure properly adapted for the intended purpose.

The metal strap sheet material is generally disposed vertically edgewise in the loop structure, and the walls of the carrier bands 5 and 6 extend at a slight angle from the vertical to conform to the tapers of the side walls 3 of the pails 1 and 2. The diameters and dispositions of the carrier bands are such that the latter will flatly encompass and engage on the peripheries of the side walls of the pails adjacent to but spaced from the tops of the latter, as clearly illustrated in Figure 1.

For removably securing the pails 1 and 2 in the improved holder a novel clamping element is provided. The latter comprises an oblong clamping plate 14 having depending end lugs 15, which are adapted for engaging adjacent top portions of the top rims of the pails 1 and 2. The clamping plate 14 is fixed to the upper end of a vertically disposed bolt 16, which latter extends through the center of the cross-bar 9. An adjusting nut 17 is engaged on the lower end of the bolt 16 and operable for adjusting a spiral tensioning spring 18 which is mounted on the bolt between said nut and the under face of the cross-bar. The bolt is revoluble and vertically shiftable in the cross-bar, and a stop disk 19 is fixed thereon to limit the downward movement of said

bolt through the cross-bar, whereby the action of the spring 18 will hold the bolt in the vertical position in the cross-bar when the clamping plate is disengaged from the pails 1 and 2. A vertically disposed finger ring 20 is fixed on the top of the clamping plate 14 for facilitating the manipulation of the clamping element when securing or releasing the pails 1 and 2 in the holder structure.

When the clamping plate 14 is disposed parallel to the cross-bar 9, the former will be in the releasing or disengaged position, and when the clamping plate is shifted to extend at right angles to the cross-bar, the depending lugs 15 will overlap and engage the top rims of respective pails 1 and 2.

To secure the pails 1 and 2 in respective carrier bands 5 and 6, the operator simply inserts his finger in the ring 20 and elevates the clamping plate 14 against the action of the spring 18. The clamping plate is then turned at right angles and lowered upon the top rims of the pails 1 and 2. The action of the spring will tensionally hold the clamping plate in engagement with the pails, whereby the latter will be securely clamped and held in the holder. Further, the engagement of the lugs 15 on the top rims of the pails will eliminate the tendency of the latter to sag at the free sides of the carrier bands, particularly when said pails are weighted by their contents.

The present invention provides a most efficient device of its kind, which will securely hold and

5 carry a pair of pails, which allows the convenient removal of either of the pails for independent emptying purposes, or for independent pail replacement when required, and which may be economically constructed and employed for all purposes wherein applicable.

What I claim is:

A holder for a pair of pails comprising the combination of a continuous strip of material 10 formed to provide a pair of carrier bands for receiving and supporting the pails and further being formed to provide a constricted neck between said bands, a handle fixed to said neck, a cross-bar secured in said neck, a bolt mounted in said cross-bar and being vertically and revolvably shiftable in the latter, a spiral spring mounted on said bolt below said cross-bar and abutting against the latter, a nut threadedly engaged on the lower end of said bolt for retaining and adjusting said 15 spring on said bolt, a stop disk fixed on said bolt above said cross-bar for limiting the downward movement of said bolt in said cross-bar, a clamp plate fixed to the upper end of said bolt and being provided with depending end lugs overlapping 20 and engaging the top rims of respective pails to retain the latter in said bands, and a vertically disposed finger ring fixed to the top of said clamping plate for facilitating the manipulation of the latter to secure and release the pails in 25 30 said bands.

ANNA WEBER.
